CLAIM

The ornamental design for a multi-mode smart phone, as
shown and described.

DESCRIPTION

FIG. 1 is a front view of the new design for a multi-mode
smart phone.

FIG. 2 is a rear view of the new design for a multi-mode
smart phone.

FIG. 3 is a left side view of the new design for a multi-mode
smart phone.

FIG. 4 is a right side view of the new design for a
multi-mode smart phone.

FIG. 5 is a top view of the new design for a multi-mode
smart phone.

FIG. 6 is a bottom view of the new design for a multi-mode
smart phone.

FIG. 7 is a perspective view of the new design for a
multi-mode smart phone.

FIG. 8 is another perspective view of the new design for a
multi-mode smart phone, shown only in this view with the
rear stand extended; and,

FIG. 9 is another perspective view of the new design for a
multi-mode smart phone.

The broken lines shown in FIGS. 8 and 9 illustrate projector
effects and do not form part of the claimed design.

1 Claim, 9 Drawing Sheets
